[57] CLAIM

The ornamental design for handle for a saw or similar article, as shown and described.

DESCRIPTION

FIG. 1 is a perspective view of handle for a saw or similar article showing my new design;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view thereof;

FIG. 7 is a bottom plan view thereof;

FIG. 8 is a perspective view thereof showing a saw blade in the open position;

FIG. 9 is a perspective view thereof showing a saw blade in the closed position.

The broken line showing of the saw blade in FIGS. 8 and 9 is for illustrative purposes only and forms no part of the claimed design.
